ROCK DUSTER

Albert J. Gurney and Glenn D. Gurney, Canton,
Ohio, assignors to The American Mine Door
Company, Canton, Ohio, a corporation of Ohio

Application July 2, 1945, Serial No. 602,700

4 Claims. (Cl. 302—50)

1

The invention relates to apparatus for spraying rock dust in coal mine tunnels and similar places, to cover or mix with the coal dust upon the floors, walls and ceilings to prevent explosion of the coal dust.

It is common practice to spray the interiors of mine tunnels and the like with apparatus of this general character, and such apparatus as is at present used for this purpose comprises generally a hopper containing the rock dust and having screw means in its lower portion for feeding the rock dust to a feed tube or pipe through which an air blast is passed for spraying the rock dust from a suitable nozzle connected to said feed tube.

Difficulty has been experienced in the past by the rock dust packing and arching over the feed screw in the bottom of the hopper, so the uniform feeding of the rock dust to the feed tube is frequently interrupted, requiring manual breaking up of the caked and arched rock dust from time to time.

In order to overcome this difficulty the structure disclosed in Gurney Patent No. 1,781,509 of November 11, 1930, was produced, wherein a pair of parallel feed screws were located in the bottom of the hopper and an agitator shaft was located above the screws and provided with a multiplicity of radial pins or fingers for continually breaking up any packed or caked portions of the rock dust and preventing it from arching above the feed screws.

Such construction overcame the difficulty to a considerable extent, but the agitator shaft was found to be dangerous as there was a possibility of workmen getting a glove or sleeve caught upon the rotating, radial fingers thereof, causing injury to the workman.

Another difficulty encountered in the general type of rock dusters now in common use is in the connection of pipes and fittings from the blower to the feed tube. It is also pointed out that in the present form of rock dust a low speed screw is used for feeding the rock dust through the hopper to the feed tube, and it is thought that the tendency of the rock dust to pack and arch above the feed screw may be at least partly due to the slow movement of the screw, which in ordinary practice rotates at less than one hundred

2

revolutions a minute, generally at a speed of about sixty-six revolutions per minute.

The present invention has for its object the provision of a rock duster which overcomes the difficulties and objections above referred to.

A specific object of the invention is to provide a rock duster which prevents packing and arching of the rock dust above the feed screw.

Another object is to provide a rock duster in which an agitator shaft is not required above the feed screw to prevent caking or packing of the rock dust.

A further object of the invention is to provide a rock duster having a single high speed feed screw located through the hopper for uniformly feeding rock dust to the feed tube.

A still further object is to provide a rock duster in which an air chamber is located along one wall of the hopper and connected at one end to the blower and at its other end to the feed tube, whereby the usual pipes and fittings between the blower and the feed tube are dispensed with and a continual blast of air is passed along one wall of the hopper, producing an agitation of the rock dust within the hopper and tending to prevent packing or arching thereof above the feed screw.

Another object of the invention is to provide a rock duster having a check valve located in the feed tube to prevent back pressure of the air blast into the hopper.

The above objects, together with others which will be apparent from the drawings and following description, or which may be later referred to, may be attained by constructing the improved rock duster in the manner illustrated in the accompanying drawings, showing a preferred embodiment of the invention, in which:

Figure 1 is a top plan view of the improved rock duster;

Fig. 2 a vertical, longitudinal section through the rock duster, taken as on the line 2—2, Fig. 1;

Fig. 3 an enlarged, vertical, transverse section through the rock duster, taken as on the line 3—3, Fig. 1;

Fig. 4 an enlarged sectional view through the gear housing, taken as on the line 4—4, Fig. 1; and,

Fig. 5 an enlarged, horizontal, longitudinal section through the feed tube, showing the check

valve therein, taken as on the line 5—5, Fig. 2.

The rock duster is designed to be moved through mine tunnels or the like, and may be arranged to be conveyed upon a railroad track by means of a locomotive, and for this purpose the apparatus is mounted upon a carriage which may comprise the frame 10 in which are journalled axles 11 upon which are mounted the flanged wheels 12 adapted to run upon rails 13.

A hopper is mounted upon the frame, for containing a supply of rock dust, this hopper preferably being of substantially V-shape as best shown in Fig. 3, and comprising the downwardly converging side walls 14 and the front and rear walls 15 and 16 respectively.

Overhanging, horizontal shelves 17 may be formed at the upper ends of the side walls of the hopper, terminating in the depending reinforcing flanges 18, the lower edges of which may be attached to the frame 10.

An important feature of the invention consists in an air chamber 19 located upon one side of the hopper and enclosed by one side wall 14 of the hopper and a wall 20 parallel thereto, the bottom wall 21, a portion of the adjacent shelf 17 forming the top wall of the air chamber and extensions of the front and rear walls 15 and 16 of the hopper forming the front and rear walls of the air chamber.

A single high speed feed screw 22 is located longitudinally through the lower portion of the hopper, the shaft thereof being journalled through the rear wall 16 of the hopper as indicated at 23 in Fig. 2, while the forward end of the feed screw is extended through an opening 24 in the front wall 15 of the hopper and into the inner tube 25 located within the feed tube 26 which is connected to the front wall of the hopper.

A spider 27 is fixed upon the forward end of the inner tube 25 and has a bearing 28 formed thereon within which is slidably mounted the stem 29 of the check valve 30 which is normally seated in the end of the inner tube 25 as by the spring 31.

The feed tube 26 extends slightly beyond the inner tube 25 and is provided with the flanged end 32 to which a nozzle of any usual and well known design, such for instance as indicated in the Gurney Patent No. 1,781,509 above referred to, may be attached for spraying the rock dust within a mine tunnel or the like. The feed tube 26 has the elbow 33 formed thereon which communicates with the air chamber 19 as best shown in Fig. 5.

The shaft 34 of the feed screw may have a flexible coupling 35 thereon and is extended into the gear housing 36 mounted near the rear portion of the frame 10, a sprocket wheel 37 being fixed upon said shaft within the housing and connected as by the chain 38 with a sprocket 39 upon the shaft 40 of the motor 41, a flexible coupling 42 being preferably located in the motor shaft also. A starter 43 is provided upon the rear portion of the frame 10, for the motor 41.

A blower 44 is mounted adjacent the rear end of the hopper and is connected, as by the pipe 45, to the air chamber 19 so that when the blower is being operated a continuous blast of air is passing through the air chamber 19 and into and through the feed tube 26, picking up rock dust which is fed into the feed tube by means of the feed screw and blowing the same through the nozzle for spraying the ceilings, walls and floors of coal mines, tunnels and the like.

A clutch 46 is provided upon the feed screw

shaft 34, within the housing 36, for manually engaging or disengaging the sprocket wheel 37 with the shaft 34, this clutch being operated through the vertical shaft 47 and hand lever 48. Thus the feed screw may be started or stopped at any time during the operation of the motor.

The blower shaft 49 may also be provided with a flexible coupling 50 and extends into the gear housing 36 having the sprocket 51 fixed thereon and connected as by the chain 52 with the sprocket 53 upon the motor shaft 40 whereby the blower will be operated continuously during the operation of the motor.

The feed screw 22 being connected directly to the motor is driven at high speed, preferably about twelve hundred revolutions per minute. The continual blast of air passing through the air chamber 19 has a tendency to vibrate the adjacent side wall 14 of the hopper, and it has been found in actual practice that this vibration of the hopper together with the high speed of the screw produces sufficient agitation of the rock dust within the hopper to prevent the same from packing or arching over the screw, and dispenses with the necessity of providing twin screws and an agitating shaft, as has been customary in the past.

We claim:

1. A rock duster comprising a hopper, a feed screw in the lower portion of the hopper, means for rotating the feed screw, a feed tube communicating with one end of the hopper, the feed screw being extended into said feed tube, an air chamber formed along one side of the hopper and communicating at its forward end with the feed tube, the adjacent side wall of the hopper forming one side wall of the air chamber, and means for passing an air blast through said air chamber to the feed tube so as to vibrate said adjacent side wall of the hopper.

2. A rock duster comprising a hopper, a feed screw in the lower portion of the hopper, means for rotating the feed screw, a feed tube communicating with one end of the hopper, the feed screw being extended into said feed tube, an air chamber of a height and length corresponding to the height and length of the hopper formed along one side of the hopper and communicating at its forward end with the feed tube the adjacent side wall of the hopper forming one side wall of the air chamber, and means for passing an air blast through said air chamber to the feed tube so as to vibrate said adjacent side wall of the hopper.

3. A rock duster comprising a hopper, a feed screw in the lower portion of the hopper, a motor, sprocket and chain gearing connecting the feed screw directly to the motor for rotating the feed screw at a speed of about 1200 R. P. M., a feed tube communicating with one end of the hopper, the feed screw being extended into said feed tube, an air chamber formed along one side of the hopper and communicating at its forward end with the feed tube, the adjacent side wall of the hopper forming one side wall of the air chamber, and means for passing an air blast through said air chamber to the feed tube so as to vibrate said adjacent side wall of the hopper.

4. A rock duster comprising a hopper, a feed screw in the lower portion of the hopper, a feed tube communicating with the forward end of the hopper, the feed screw being extended into said feed tube, an air chamber formed along one side wall of the hopper and coextensive therewith, said air chamber communicating at its for-

ward end with the feed tube the adjacent side wall of the hopper forming one side wall of the air chamber, a blower communicating with the rear end of the air chamber for passing an air blast through said air chamber to the feed tube so as to vibrate said adjacent side wall of the hopper, a motor, sprocket and chain gearing connecting the motor to the blower and sprocket and chain gearing connecting the motor directly to the feed screw.
